Primary Examiner — Cynthia Underwood(74) *Attorney, Agent, or Firm* — Foley & Lardner LLP(57) **CLAIM**

We claim the ornamental design for a cup, as shown and described.

DESCRIPTION

FIG. 1 is a perspective front view of the cup;

FIG. 2 is a side view of FIG. 1;

FIG. 3 is a top view of FIG. 1; and,

FIG. 4 is a bottom view of FIG. 1.

The ornamental design which is claimed is shown in solid lines in the drawings: The broken lines in the drawings are for illustrative purposes only and form no part of the claimed design.
